(57) **CLAIM**

The ornamental design for a power toothbrush with charger base, substantially as shown and described.

DESCRIPTION

FIG. 1 is a front perspective view of the toothbrush portion of the power toothbrush with charger base embodying our new design, shown without the charger base for clarity of illustration;

FIG. 2 is a front view of FIG. 1;

FIG. 3 is a rear view of FIG. 1;

FIG. 4 is a side view of FIG. 1, the opposing side being a mirror image;

FIG. 5 is a front perspective view of the power toothbrush with charger base;

FIG. 6 is a front view of FIG. 5;

FIG. 7 is a rear view of FIG. 5; and,

FIG. 8 is a side view of FIG. 5.

The broken line showing of bristles in FIGS. 1, 2, 4-6, and 8 are included for the purpose of illustrating environmental structure which forms no part of the claimed design.
